Patented July 25, 1916.

UNITED STATES PATENT OFFICE.

ROTHCHILD F. THORNDIKE, OF CHELSEA, MASSACHUSETTS.

CIGARETTE-BOX.

1,192,707.

Specification of Letters Patent. Patented July 25, 1916.

Application filed May 26, 1916. Serial No. 99,969.

To all whom it may concern:

Be it known that I, ROTHCCHILD F. THORNDIKE, of Chelsea, in the county of Suffolk and State of Massachusetts, have invented 5 certain new and useful Improvements in Cigarette-Boxes, of which the following is a specification.

This invention relates to cigarette boxes and particularly of the type which comprises 10 two members hingedly connected. With boxes of this character as usually now employed, the cigarettes are usually laid loosely in the bottom member of the box and must be picked therefrom after the top or 15 cover is raised. Then when the cover is closed there is frequently liability of damage to the cigarettes by tearing or mutilating them as the sides of the cover close onto the bottom member.

20 The object of my invention is to provide an improved attachment for boxes of this character which, when the cover is raised, will automatically elevate the cigarettes from the bottom member of the box and prevent 25 sent them in a position for easy access.

My invention consists in the attachment, and in the box having a pocket attachment, substantially as hereinafter described and claimed.

30 Of the accompanying drawings Figure 1 is a perspective view of a cigarette box embodying my improvements, said box being open to give access to the cigarettes. Fig. 2 is a sectional view of the same. Fig. 3 is a 35 similar sectional view but with the box closed. Fig. 4 is a plan view of the blank from which my improved pocket attachment is economically made. Fig. 5 is a perspective view of the pocket attachment, made 40 from a blank such as illustrated in Fig. 4, folded and ready to be attached to the box members as shown in Figs. 1 and 2.

Similar reference characters indicate similar parts in all of the views.

45 A box of well-known form and construction comprises a bottom member 12 and a cover or top member 13 hinged to the bottom member at 14, the hinge usually consisting of the label which is employed to extend partly 50 or wholly around the box. The box illustrated in the drawings is proportioned to hold cigarettes in two layers, but my invention is not limited thereto, as the box may be 55 differently proportioned to hold the cigarettes in a single layer.

My improved attachment, as illustrated

in the drawings, comprises a blank cut in the form indicated in Fig. 4, and creased or scored as indicated in that figure. The different portions or sections illustrated in Fig. 4 comprise the rectangular portions 15 and 16 which are connected by a narrower portion 17, flaps 18 and 19 being adapted to be overlapped and adhesively connected. Extending downwardly from the portion 15 is 60 a flap which is creased to present portions 20 and 21. The portions 16 of the blank is of greater length than the portion 15 and is provided with a flap 22. When the blank shown in Fig. 4 is folded to the condition 65 illustrated in Fig. 5, the flaps 18 and 19 being adhesively connected, the portion 20 is folded in so as to form the bottom of a 70 pocket, the walls of which consist of the portions 15, 16, 17 and 19. This pocket is very 75 readily secured in proper position relatively to the bottom and cover members of the box by simply applying a suitable adhesive to the rear face of the portion 21, and the rear face of the portion 22, pressing the portion 80 21 against the inner face of the rear wall of the bottom member 12 of the box, and pressing the flap 22 against the inside of the cover of the box close to that portion of the cover which is uppermost when the cover is raised 85 as shown in Fig. 2. The pocket may be filled with the cigarettes either before or after it is located and secured as just described.

When the box is closed the pocket and the 90 contents thereof assume the position shown in Fig. 3 but when the cover is raised, the pocket is automatically projected somewhat forward from the cover 13, this being due to the fact that the hinge 23 formed by the 95 crease between the portions 20 and 21, is above the hinge 14 of the cover. As the cover is raised, said cover and the pocket turn on different centers presented by the hinges 14, 23, but since the portion 22 is adhesively connected to the inside of the cover, 100 that portion of the pocket attachment cannot yield and the rear wall of the pocket becomes automatically somewhat bowed. It is this yielding connection of the pocket which 105 causes the latter to project the articles forward as the cover is raised. That is the yielding connection is somewhat resilient, because the upper extended portion of the rear member 16 of the pocket is capable of springing or 110 curving somewhat as indicated in Fig. 2.

It will readily be understood that the at-

tachment may be differently formed to fit other shapes or proportions of boxes. In fact my invention contemplates the separate manufacture and sale of attachments such as shown in Fig. 5, either shaped and proportioned just as shown in that figure or differently proportioned to fit other proportions of boxes.

The pocket thoroughly protects the cigarettes, as the inner wall of the pocket provides a smooth surface, and during the opening or closing of the box nothing can contact with the cigarettes to injure them in any way. And yet a simple raising of the cover or top member lifts all of the cigarettes *a* to accessible position.

Having now described my invention, what I claim is:

1. A box of the character described comprising a bottom member, a cover hinged

thereto, and a pocket having front, rear, side and bottom portions, the bottom portion having a flap adhesively secured to the rear wall of the bottom member of the box, and the rear portion of the pocket having an upwardly extended flap adhesively secured to the inside of the cover of the box.

2. A pocket attachment for boxes of the character described, comprising a blank folded to present front, rear, side and bottom portions, the bottom portion having a flap adapted to be adhesively secured to the rear wall of the bottom member of a box and the rear portion having an upwardly extended flap adapted to be adhesively secured to the inside of the cover of the box.

In testimony whereof I have affixed my signature.

ROTHCHILD F. THORNDIKE.
